(57) **CLAIM**

The ornamental design for a display screen with animated graphical user interface, as shown and described.

DESCRIPTION

FIG. 1 is a front view of a first image in a sequence of successive images showing a display screen with animated graphical user interface;

FIG. 2 is a front view of a second image in the sequence of successive images thereof;

FIG. 3 is a front view of a third image in the sequence of successive images thereof;

FIG. 4 is a front view of a fourth image in the sequence of successive images thereof; and,

FIG. 5 is a perspective view of the image of FIG. 1 being applied to an exemplary user device.

The outer uneven-length broken line rectangle and upper and lower broken line rectangles illustrate an electronic device that is an exemplary environment of the article. The inner uneven-length broken line at the periphery of each figure illustrates a display screen and the remaining broken lines in each figure illustrate portions of the animated graphical user interface. None of the broken lines form part of the claimed design.

The appearance of the transitional image sequentially transitions between the images shown in FIGS. 1-4. The process or period in which one image transitions to another image forms no part of the claimed design.
